UNITED STATES PATENT OFFICE.

ALLIE LEE STANDARD, OF TUSCOLA, TEXAS.

WATER-CYCLE.

No. 837,973.

Specification of Letters Patent.

Patented Dec. 11, 1906.

Application filed September 29, 1905. Serial No. 280,647.

To all whom it may concern:

Be it known that I, ALLIE LEE STANDARD, a citizen of the United States, residing at Tuscola, in the county of Taylor and State of 5 Texas, have invented a new and useful Water-Cycle, of which the following is a specification.

This invention relates to water-cycles, and has for its object to provide certain new and 10 useful improvements in this class of devices whereby the same may be conveniently propelled, steered, and otherwise handled.

A further object of the invention is to so dispose the propeller-wheel as to have the 15 same exert a lifting tendency as well as a driving force, thereby to add to the buoyancy of the device.

With these and other objects in view the present invention consists in the combination 20 and arrangement of parts, as will be herein-after more fully described, shown in the accompanying drawings, and particularly pointed out in the appended claim, it being understood that changes in the form, proportion, size, and minor details may be made 25 within the scope of the claim without departing from the spirit or sacrificing any of the advantages of the invention.

In the accompanying drawings, Figure 1 is 30 a side elevation, partly in section, of a water-cycle embodying the features of the present invention. Fig. 2 is a rear elevation thereof. Fig. 3 is a detail plan view of one of the floats.

Like characters of reference designate corresponding parts in each figure of the drawings.

For the support of the framework of the present device there is a front cylindrical float 1, having a conical forward end, and two rear floats 2 and 3, located equally at opposite sides of the front float and also provided with conical front ends. A steering head or bar 4 rises from the front float 1 substantially midway of its ends and is provided at its upper end with a handle-bar 5. A downwardly and rearwardly inclined reach-bar 6 extends from the steering-head at a suitable height above the float 1. This reach-bar is provided with a fork 7 of suitable length, 45 which has the ends of its side members diverged rearwardly to form braces 8, which are connected to a cross-bar 9, extending between and connecting the rear floats 2 and 3. A seat-post composed of upwardly-converged 50 bar members 10 rises from the points of intersection between the fork members 7 and the

braces 8, and an upper reach-bar 11 extends between the upper portion of the steering-head 4 and the seat-post 10. A suitable seat 12, preferably in the nature of a bicycle-seat, 55 is supported in any suitable manner upon the top of the seat-post. Downwardly and rearwardly diverged braces 13 extend from the top of the seat-post to the tops of the rear floats 2 and 3, to which they are connected in 60 any suitable manner in alignment with the cross-bar 9. A suitable coupling 14, having seats or sockets for the reception of the upper reach-bar 11, the seat-post members 10, and the braces 13, is employed to connect these 65 elements at their point of meeting. This coupling 14 also has an upright open-ended seat for the reception of a seat-post 15, which also has its lower end portion loosely received in a clip 16, fixed to the members 10 and provided with a set-screw 17 to engage the seat-post and hold the seat at any adjusted elevation. 70

Within the fork 7 is a beveled gear 18, which is journaled in suitable brackets or 75 hangers 19, carried by the fork members, the ends of the shaft of the wheel being provided with suitable pedal-cranks 20 for manipulation by the feet of the rider when mounted upon the seat 12. Within the fork 7 and in 80 mesh with the gear 18 there is a beveled pinion 21, carried upon the upper forward end of a rearwardly and downwardly inclined drive-shaft 22, which has its upper end mounted in a bearing 23, carried by the lower ends of the 85 members 10. The drive-shaft 22 extends slightly in rear of the cross-bar 9 and is mounted in a bearing 24, carried by said cross-bar, there being a suitable propeller-wheel 25, carried by the rear end of the drive-shaft in a plane at right angles to the latter 90 and inclined upwardly and rearwardly.

When the device is in use, the operator mounts upon the seat 12 and operates the propeller by means of the pedal-cranks 20, 100 whereby the device is propelled forwardly and is steered by means of the handle-bar 5. To increase the control of the device in steering, a depending fin 26, in the nature of a longitudinally-disposed blade, is carried by the 105 under side of the forward float 1, so as to obtain a sufficient purchase upon the water to effectually guide the device.

The advantage of setting the propeller at an angle to the vertical is to impart a lifting 110 power upon the device, which adds materially to its buoyancy, and therefore tends to re-

duce the power necessary to propel the device.

In addition to having the forward end of each float substantially conical I propose to have the under side thereof inclined or flared upwardly and forwardly, as clearly indicated in Fig. 1 of the drawings, whereby the float has a tendency to raise or lift itself rather than to bury itself in the water. Furthermore, the rear end of each float is tapered or reduced in width, as best indicated in Fig. 3, thereby to permit of the float leaving the water with a clear run.

Having thus described the invention, what is claimed is—

A water-cycle including a plurality of substantially cylindrical floats arranged in triangular form, said floats being each provided with a pointed terminal and having parallel top, side and bottom walls and inclined end walls, a frame connecting said floats, a steering-head forming a part of the frame and

upon which the front float is pivotally mounted, a propeller-shaft journaled in the supporting-frame and having its free end inclined 25 downwardly between the rear floats, a propeller carried by said shaft and disposed substantially in alinement with the front float, the side and bottom walls of the rear floats being smooth and unobstructed, and a longitudinally-disposed fin depending from the bottom of the front float between the pointed terminal and inclined end walls thereof and having its free end extended below and disposed in alinement with the apex of the inclined end walls of said float. 30 35

In testimony that I claim the foregoing as my own I have hereto affixed my signature in the presence of two witnesses.

ALLIE LEE STANDARD.
